UNITED STATES PATENT OFFICE.

RUBEN CHRISTOPHER MILLER HASTINGS, DECEASED, LATE OF COLUMBUS, OHIO, BY
ELIZABETH FULLER HASTINGS, EXECUTRIX, OF COLUMBUS, OHIO, ASSIGNOR TO
THE INTERNATIONAL TELEPHONE COMPANY, OF COLUMBUS, OHIO, A CORPORA-
TION OF OHIO.

TELEPHONE SYSTEM.

Application filed September 28, 1923. Serial No. 665,378.

The invention relates to party-line telephone systems and apparatus of the kind comprising magnetically operated selector disks at the substations, the rotation of which disks is controlled by sending impulses from the central station. A purpose of the invention is to provide an improved system employing the present switchboard and line circuits, with only the addition of a mechanical or master key selecting device at the exchange, and with the substitution at each substation of improved mechanism controlling the conditions of the substation instruments. It is also a purpose of the invention so to simplify the construction of the substation instruments that it will be unnecessary to provide party-line subscribers with instructions as to the use of the telephones other than the instructions now customarily given.

The invention will be described in connection with the accompanying drawings, and its novel features will be pointed out in the appended claims.

In the drawings:

Fig. 1 is a front elevation of a substation controller set adapted for use in a wall telephone.

Fig. 2 is a section on the line 2—2 of Fig. 1.

Fig. 3 is a view similar to Fig. 1, but showing some of the parts in section, and omitting some of the parts shown in Fig. 1.

Fig. 4 is a section on the line 4—4 of Fig. 1.

Fig. 5 is a section on the line 5—5 of Fig. 1.

Fig. 6 is a side view of the selecting disk.

Figs. 7 and 8 are sections on the lines 7—7 and 8—8 respectively of Fig. 6.

Figs. 9, 10 and 11 are diagrammatic views of the selecting disk and the contacts thereby controlled, Fig. 9 showing the parts in normal condition, Fig. 10 showing the parts in the position which they occupy when the receiver has not been replaced upon the hook, and Fig. 11 showing the parts in the position occupied when the receiver hook is raised after the parts were in normal position.

Fig. 12 is a diagrammatic view of the periphery of the selecting disk with the pin in the position of Fig. 9.

Fig. 13 is a similar view showing the parts in the position assumed when the called subscriber answers the call.

Fig. 14 is a view of the parts in the position corresponding to Fig. 10.

Fig. 15 is a view of the parts in the position of Fig. 11, showing the travel of the pin which controls the contact blades in the calling substation.

Fig. 16 is a similar view showing how the parts come into the position of Fig. 10 when the calling subscriber fails to hang up the receiver on completing the call.

Fig. 17 is a similar view showing the travel of the pin when the operator at the exchange station notifies the subscriber in order that he may hang up the receiver which he failed to hang up on the completion of the call.

Fig. 18 illustrates a relay not shown in Figs. 1 and 3 but provided at the substation to control certain switch blades.

Fig. 19 is a plan view of a desk telephone provided with controlling apparatus according to the present invention.

Fig. 20 is a section on line 20—20 of Fig. 19.

Fig. 21 is a section on the line 21—21 of Fig. 19.

Fig. 22 is a section, with parts in elevation through the tubular support of a desk telephone.

Fig. 23 is a section on the line 23—23 of Fig. 19.

Figs. 24 to 29 inclusive are diagrammatic views corresponding to the showings in Figs. 12 to 17 inclusive.

Figs. 30 and 30^a are respectively diagrammatic illustrations of the circuits of the calling and answering cords.

Fig. 30^b is a diagrammatic view of the circuit of the wall telephone set illustrated in Figs. 1 to 18.

Fig. 31 is a diagrammatic view of the substation circuit used in conjunction with the desk telephone of Figs. 19 to 29.

Before describing the construction of the substation instruments, a description will be given of the various circuits involved in the use of the system.

Calling the exchange operator.

Referring to Figs. 30^a and 30^b, on removal of the receiver R, the switch hook contacts

10 and 11 are closed, as well as the contacts 11 and 129. Also the raising of the receiver hook swings the pivoted arm A to close contacts 15 and 16 and open the contacts 16 and 183 of the call up alarm. This notifies the operator of the call by establishing the following circuit:—battery B (negative side), conductor 1, line relay 2, conductor 3, armature 4, contact 5, conductors 6, 7 and 8, junction 122, transmitter 9, contacts 10 and 11, conductor 12, winding 13 of induction coil C, conductor 14, contacts 15 and 16, conductors 17, 18 and 19, contact 20, armature 21, conductor 22, and ground 25 g back to battery. Energization of the line relay 2 attracts armature 27, lighting the lamp 25 through the circuit from battery B, conductor 24, lamp 25, conductor 26, armature 27, contact 28, conductor 29 and ground 20 g. The central station operator is thus notified that a subscriber desires a connection, and the answering plug P is inserted in jack J associated with the circuit in which the lamp was lit. The insertion of the plug 25 cuts out the lamp 25 and puts the operator in communication with the calling substation through the circuit from battery B', conductor 30, relay 31, conductor 32, relay 33, and sleeve contact 35 of the plug. From this point the circuit continues through conductors 36 and 37, relay 38, conductor 39, and ground g back to battery. This circuit simultaneously energizes relays 31, 33 and 38. Energization of relay 38 opens the contacts 4 and 5 and 20 and 21, thus deenergizing relay 2, whereby contacts 27 and 28 are opened and the lamp extinguished. The main lines are now free for selecting and ringing.

40 *Preliminary selecting impulse.*

Relay 33 is quick acting and relay 31 is relatively slow in acting due to the provision of copper slugs, which may be adjusted to 45 vary the energization period, which is preferably about one-fifth of a second. Thus the preliminary impulse period is in effect the period from the instant of energization of relay 33 until complete energization of relay 31. The circuit for the preliminary impulse is from battery B², conductor 40, contact 41, armature 42 and conductor 43, at the end of which current flow is divided, one part of the circuit continuing through 50 conductor 44, contact 45, armature 46, conductor 47, and the tip contact 48 of plug P. From the point of division the other part of the circuit is to contact 49, armature 50, conductor 51, and ring contact 52 of the 55 plug. From the plug tip 48, the circuit continues through contact 53, conductors 18, 17 and 54, relay 55, conductor 56 to condenser 57. At this time, the charge on the condenser is such that an impulse is drawn 60 through relay 55 (by what is known as con-

denser kick) so that armature 62' is attracted and contacts 62 and 63 are closed, armature 68 being likewise attracted to close on contacts 67 and 69. The closing of contacts 62 and 63 includes the relay 55 in the circuit, 70 through conductors 56 and 59, magnet 60 conductor 61, contacts 62 and 63, conductors 64 and 58, to ground. Current also flows from ring contact 52 to contacts 65, and conductors 7, 8 and 66 to contact 67 and armature 68, where the line wires are short circuited. From this point, the circuit continues to contact 69, conductor 70, relay 71, conductor 72, conductor 59, stepping magnet 60, conductor 61, contacts 62 and 63, conductors 64 and 58 to ground g'. It will thus be seen that the impulse is sent over both line conductors in parallel. Relay 55 has too great a resistance to pass enough current to operate magnet 60, but when armature 68 85 is closed, relays 55 and 71 are in parallel, and the magnet 60 is energized to attract its armature 6' to rotate the selector disk, hereinafter described, one step.

90 *Speaking connection.*

Speech transmission is now possible between the calling substation and the exchange through a circuit from battery B³, conductor 73, winding 74 of relay 75, conductors 76, 77 and 78, contacts 79 and 80 of the ringing key K, conductor 81, armature 82, contact 83, conductor 84, contacts 85 and 86 of the selecting key O (here shown as a dial but which may be associated with a master and machine key such as shown in Patent No. 1,588,108, June 8, 1926, on application for patent filed by R. C. M. Hastings), conductor 87, contact 88, armature 50 (the relay 33 being now fully energized) conductor 51, ring contact 52, line conductors 7 and 8, transmitter 9, contacts 10 and 11, conductor 12, coil 13, conductor 14, contacts 15—16, conductors 17 and 18, contact 53, jack tip 48, conductor 47, armature 46, contact 89, conductor 90, contacts 91 and 92, conductor 93, contacts 94 and 95, conductors 96, 97 and 98, winding 99, and conductor 100 back to battery. Energization of relay 75 prevents the supervisory lamp 115 210 from lighting by opening contacts 212 and 213.

120 *Operator's listening-in circuit.*

The operator now listens to the calling subscriber by throwing the listening key L, which places her receiver 108 on the line through the contacts 101 and 102, 103 and 104 of the key, conductor 105, winding 106 of the induction coil C', conductor 107, receiver 125 108, condenser 110 and conductor 111. By speaking into the transmitter 112, resistance in the transmitter circuit is varied, this circuit including battery B³, conductor 113, retarding coil 114, conductor 115, winding 130

116 of the induction coil C¹, conductor 117, transmitter 112, and conductor 118. The condenser 119 improves transmission by compensating for the retarding coil 114, this condenser being connected across the battery in parallel with winding 116 and transmitter 112, by means of conductors 120 and 121. At the point 122 in the substation, the circuit is divided, one branch including transmitter 9, contacts 10, 11, conductor 12, winding 13, conductor 14, contacts 15, 16, conductor 17, conductor 18, while the other branch is from 122 through condenser 123, conductor 124, winding 125, conductor 126, receiver R, conductor 128, contacts 129 and 11, and conductor 12 back to the line 18.

Calling substation.

Having learned the number of the desired substation, the operator takes the calling cord (Fig. 30) and inserts the plug P' in the line jack of the desired subscriber, and this produces a preliminary step or impulse. The impulse circuit is from battery B⁴, through conductor 130, relay 131, conductor 132, relay 133, conductor 134 to the plug sleeve 135. From this point the circuit is continued through conductors 36 and 37 associated with the called line, relay 38, conductors 39 and 22 to ground and back to the battery. The relays 131 and 133 correspond respectively with the relays 31 and 33, providing an interval of about one-fifth of a second for the impulse. This impulse is sent out over the circuit from battery B⁵, conductor 140, contact 141, armature 142, and conductor 143, to a point where the circuit is divided. One part continues through conductor 144, contact 145', armature 146, conductor 147, plug tip 148, contact 53, and thence to line 18 and to the called substation as before described. From the point of division the other part of the circuit is through conductor 149, armature 150, conductor 151, ring contact 152, and contact 65 to line 7 and relay 71, as before described.

After the lapse of the impulse interval, the relay 131 attracts its armatures and the connections are ready for the operator to call the desired station. To dial or select the operator throws the calling key 153, closing the impulse circuit of the dial or other impulse sending device. The circuit is from battery B⁶, conductor 154, contacts 155, 156, and conductor 157 to the point where the circuit is divided, one part going through conductor 158, contacts 159, 160, conductor 161, contact 145, armature 146, to the plug tip 148. The other part of the circuit is to the ring contact 152, through conductor 162, contacts 163, 164, conductor 165, contact 166, armature 150 and conductor 151. The desired number of impulses is thus sent out on the two sides of the line in parallel,

stepping the disk D to the desired extent, whereupon the pin p on the disk D (Fig. 30^b), at the wanted station on the party line which will hereinafter be described in detail, closes the contacts 167, 168 of the call-up alarm circuit. The operator then restores the calling key 153.

Call-up alarm.

The operator throws the ringing key 169, whereby a circuit from the A. C. generator 170 is established as follows: conductor 171, contacts 172, 173, conductor 174, armature 175, contacts 176, conductor 177, contacts 178, 164 of the restored calling key 153, conductor 165, contact 166, to plug ring 152, conductors 7 and 8, condenser 123, conductor 179, bell 180, conductor 181, contacts 168, 167, conductor 182, contacts 183 and 16 and conductor 17 to the plug tip 148. From this point the circuit is completed to the generator through 147, 146, 145, 161, 160, 184, 185, contacts 186, 187 and conductor 188.

Supervision.

Upon raising of the receiver hook at the called substation, the switch hook contacts are closed and the call-up alarm contacts 16, 183 opened. The following circuit is then established: battery B⁷, conductor 195, winding 196 of relay 193, conductors 197 and 198, contacts 199, 173 of the now restored ringing key 169, conductor 174, armature 175, contact 176, conductor 177, contacts 178, 164, to ring contact 152, through the transmitter and the receiver hook switch in the substation back to plug tip 148 and ringing key contact 189, conductors 190 and 191, winding 192 and conductor 194 to battery. The armature 203 is thus removed from contact 204 to extinguish the supervisory lamp 201, whose circuit includes in addition to the contacts mentioned, battery B⁸, the conductors 200, 202 and 205, contact 206, armature 207 and conductor 208. When the circuit including battery B⁷ is broken in the substation by the called party hanging up, the deenergized relay 193 permits the circuit of the supervisory lamp to be closed.

The supervisory lamp 210 of the answering cord circuit (Fig. 30^a) hereinbefore referred to, which is broken when the relay 75 is energized, similarly contains battery B⁹, conductors 209, 211 and 214 and the contacts 212 and 213 through contact 215, 216, conductor 17 to ground.

The plug of the calling circuit is connected to the plug of the answering circuit by the conductors 218 and 220 through condenser 219, and the conductors 221 and 223 through condenser 222.

Both the calling and answering circuits include timing relays to ensure that the relay 55 in the substation may have time to unlock before the establishment of the ringing

and talking circuits. In Fig. 30^a, a battery B¹⁰ is in circuit with timing relay 224, conductors 225 and 226. Where the latter is connected to conductor 227, the circuit is divided, one part being through contacts 247, 248 and conductor 249 to ground, while the other part is through conductors 227, contacts 228 and 229, conductor 230 through contacts 213, 216, conductor 217 and ground.

10 The break is at contacts 82 and 83.

In Fig. 30, the positive side of battery B'' is grounded at 252'. The other side is connected to the following circuit:—conductor 231, timing relay 232, conductor 233 to conductor 234, where the circuit is divided, one part being through contacts 250 and 251, conductor 252 to ground, while the other part is through conductor 234, contact 235 and 236, conductors 237 and 205, and contacts 206 and 207 to ground. The break occurs at contacts 175 and 176. The negative side of the line is opened only during the selecting periods.

In Fig. 30^a the operator's answering plug circuit includes an impulse sender, so that when the calling substation is connected with a substation on another line, the disks in all the substations on the line with the calling substations may be stepped to the zero position after completion of the call. Impulses are sent out from battery B¹², through conductor 239, contacts 240 and 241, and conductor 242 at the end of which the circuit divides. One part passes out on one side of the line through conductor 243, and contacts 244 and 91 to the plug tip 48, while the other part passes out on the other side of the line through conductor 245, and contacts 246 and 86 to ring contact 52. The circuit in the substation for actuating the stepping magnet 60 has already been described.

Structure of substation instrument.

Referring to Figs. 1 to 18, a wall telephone comprises a support 1' to which is removably attached a base 2' provided with supporting standards 3'. In the latter is mounted a shaft 4' having one end reduced at 4'', and at its other end carrying a ratchet 5'. The armature 6' of the stepping magnet 60 has attached to it and to the standard 3' a toggle 7' which is spring urged to pull the armature away from the magnet by a spring 8', assisted by a spring 11' which is attached at one end to the standard and at the other to the operating pawl or detent which is reciprocated by the armature to step the shaft.

60 The disk D is composed of two plates 12' and 13' of different diameters whereby the disk 13' provides an annular shoulder in which are formed guide ways 15' and 16' and a notch 18'. The disk may be adjusted on the shaft so that in the various substations on the line, the disks may have differing nor-

mal or zero positions. In the body of the disk are two apertures 13'' and 14', and on the periphery of plate 12' is an inclined hump or projection 17', to enable the pin N, as hereinafter described, to ride upwardly to 70 the level of the periphery of plate 13'.

On the reduced end of the shaft is mounted a sliding sleeve or yoke 19' adapted to turn with the shaft, and urged to the left (Fig. 2) by a spring 20'. Pins 21' and 21'' are pivoted to the sleeve or yoke, and extend through the openings 13'' and 14' in the disk. Said pins are connected to two levers 23', fulcrumed on supports 22' which are secured to the disk. One lever carries a switch point 24' and the other a shoe or tongue 25'. The switch is adapted to enter the guideway 15' and the shoe is adapted to enter the notch 18' when the sleeve is moved against the tension of the spring 20'. The switch provides a double pasageway into the guide 15' as shown in Fig. 12.

The base 2' carries a support 40' on which are mounted the switches 15, 16 and 183 before referred to, as well as the pivoted lever 90 A to which the central switch blade 16 is attached. The pin N is carried by the arm A, and it cooperates with the periphery of the disk D to control the contacts 15, 16 and 183.

A lever 26' pivoted at 27' to one of the standards is adapted to be swung when the receiver hook rises so as to move the sleeve against the tension of the spring. To this end, the lever is engaged by a plunger 29', which is preferably of insulating material 95 provided with a metal sleeve 30', and adapted to reciprocate in an opening in the standard to which the lever is pivoted. The outer end of the plunger is engaged by a roller 29'' on a pin 31'', the latter being mounted in a 100 link 31'. The pin engages the hooked ends 10'' of the contact spring 10, so that when the receiver is on the hook, the contacts 10, 11 and 129 are separated as shown in Fig. 1. The end of the link opposite the pin 31'' is 110 pivoted to a short lever 32' attached to the receiver hook R', which is pivoted at 33'. The sleeve 19', is provided with rollers 115 which engage the surface of the lever 26'. The pin 31'' is pivoted to the lever 26' at 34'.

The shaft 4' is provided with a radial 115 projection 36' which is adapted to be engaged by the hook 35' at the zero position when the relay 71 is energized. This relay is mounted as shown in Figs. 1 and 4, the hook 35' being secured to its armature 124'. The relay 55 (Fig. 18) may be mounted in any convenient place, preferably the bell box of the wall set. In Fig. 18 the relay is shown as being carried by a bracket 37'', and has only one armature 38', although for convenience in indicating the circuits, this relay is shown in Fig. 30^b as having two armatures 68 and 62'. In Fig. 18, the one armature performs the functions of the two armatures shown in Fig. 30^b, as 130

its arm 39' engages the lowermost contact 62 to close the contacts 62 and 63, and the contact 62 is connected with the contact 69 in such way that contacts 67, 68 and 69 are brought together simultaneously with the closing of contacts 62 and 63.

The pivoted arm A carries a projection 58' to provide a luminous visual signal through an aperture in the casing of the instrument. This member may be coated with radiant paint, and when the arm A is moved to one side of the disk to indicate that one of the substations on the line is busy, as indicated in Fig. 10, a visual signal of this condition will be given.

In Figs. 1 and 3, it can be seen that the contact spring 167 of the call-up alarm circuit has a bowed end adjacent the disk D so as to be engaged by the pin p projecting from the disk in the axial direction. In this way, the movement of the disk closes the contact blades 16 and 183 of the call-up alarm circuit in the substation.

In Figs. 19 to 29, a modified form of the invention is shown, which is adapted for use in a desk telephone comprising the usual tubular support 41' mounted on a circular base. A lever 42' is pivoted in the support so as to be oscillated by movement of the receiver hook R'. The lower end 43' of the lever projects into the base 44', and engages against a lever 45' in such manner that when the receiver hook is raised, the lever 43' permits the lever 45' to be actuated by a spring in such manner as to move a slidable plate 47' along the shaft 4''.

The periphery of the disk D' in Figs. 19 to 29 is somewhat different from that of the disk in the embodiment above described. This disk is provided with an annular shoulder but the grooves 48' are of such depth (Fig. 21) that the lower surface of the periphery of the disk (corresponding to the periphery of 12' in Figs. 1 to 18) is also grooved. In the present embodiment, it is unnecessary to have the pins extending through the disk and operating the levers supported by the disk and carrying the switch and shoe. Referring particularly to Figs. 20 and 21, it will be seen that the lever 45' has a forked end 46' carrying rollers which engage the slidable disk 47' which is spring urged away from the disk D'. On the slidable disk are mounted two arms 50' which enter the grooves 48', and have projections 51' of a height equal to the depth of the grooves in the annular shoulder. When the disk 47' is projected to carry the projections 51' into the notches as shown for instance in Fig. 28, the arms 50' are flush with the lower surface of the disk, whereby the pin N' on a pivoted arm contacting the contacts 167' and 168' may ride over the arm 50' as shown in Fig. 26.

The disk D' has two normal positions and

goes through two selective cycles in a single complete revolution, and for this reason it is provided with two pins 52' corresponding to the single pin p of Figs. 1 to 18, which pins are adapted successively to engage the contacts 167' and 168' of the call-up alarm circuit. In consequence of this modification of the disk, its shaft 4''' is provided with two diametrically opposite, radially extending arms 53' adapted to be caught by the hook 35' at the zero positions, said hook or stop arm being operated from the relay 71 as before described. The shaft 4''' also carries two oppositely extending arms 55', each provided with a signal plate 56' adapted to be shifted into view before an aperture 57' in the base when the slidable disk 47' is shifted by the raising of the receiver hook. These plates, like the member 58' of Figs. 1 to 18 are preferably coated with luminous paint so as to be visible in the dark.

Referring now to Figs. 9 and 12, the pin N is shown in the position when the receiver is on the hook and the disk is in the normal or zero position. When the receiver hook goes up, the switch 24' moves the pin in the calling station to the position of Figs. 11 and 15, thus separating the ringing contacts 16 and 183, and closing the contacts 15 and 16. When the operator plugs in, the disks in every substation on the line are moved one step, as will be appreciated. In all the stations except that calling the pin is switched by guideway 15' to the position of Fig. 10, following the dash line course of Fig. 12 over plate 12'. The talking contacts 15, 16 at these stations cannot therefore be closed and these stations are shut out from the calling party line. At the calling station, the pin is, throughout the revolution of the disk, on the talking side thereof, as shown in Fig. 11 and by dash lines in Fig. 15. To ring the called station the exchange operator dials its disk until the pin is in front of the shoe 25', at which position the pin p closes ringing contacts 167 and 168, the pin N being shifted through notch 18' when the receiver hook in the called station is raised. This breaks the ringing circuit at contacts 16, 183 and puts the pin on the talking side of the disk. If, on completion of the call, both receivers are hung up, and the disks in all the substations of the line are stepped to the zero position, the pins N at the calling and called stations return to normal position by entering the inclined slots 16' and the guideway 15' as shown by dash lines in Fig. 12. In all the substations not involved in the call, the pins N remain in the locked out position at Fig. 10, following the dash line course of Fig. 17. However, should the calling or called party fail to hang up, the pin will, when the disk gets to zero, be in the position of Fig. 13. In this position, the subscriber

cannot call the exchange because the pin is behind the switch point. But the exchange operator dials the disk until the pin p gets to the ringing position, the pin riding up on the hump 17'. The pin is spring mounted so that it can move in a vertical direction until it is resting on shoe 25' as shown in Figs. 14 and 16. Calling of the subscriber directs his attention to the condition of the receiver hook, on which he again hangs the receiver. This retracts the switch point 24' and the shoe 25' to the Fig. 12 position, so that the pin drops down in front of shoe 25'. The disk is then stepped 15 to zero where the pin N moves in front of the switch 24' (see dash lines of Fig. 17). Normal conditions are thus restored and the substation is prepared to make or receive calls.

Referring now particularly to the desk set whose circuit is shown in Fig. 31, the normal or zero position of the disk and pin is shown in Fig. 29, all the receivers being on their hooks. In this modification, it 25 is to be noted, the contacts 167' and 168' are used in lieu of the several contacts 167, 168, 15, 16 and 183 of Fig. 30^a.

When the receiver hook at the calling substation goes up, the contacts 10^a, 11^a and 30 129 are closed and the parts assume the position of Fig. 28, the operator's signal lamp 25 being illuminated from battery B, by closing of the circuit of relay 2, at 10^a and 11^a and at 167' and 168'. This circuit, 35 in the station, is from conductor 7^a, to conductor 75^a, primary of the induction coil, conductor 12^a, receiver hook contacts, transmitter 9^a, contacts 168' and 167' to the other side 18^a of the line.

On plugging in to answer the call, the lamp 25 is extinguished in the manner already described, by energization of relay 38 from battery B' of Fig. 30^a, and the insertion of the plug in the jack sends out 40 an impulse on the line in parallel, as has been described, so that the disks 9' in every substation on the line, including the calling substation, are all moved one step, by energization of magnet 60^a. From the tip contact of the jack, the preliminary impulse circuit is through conductors 18^a and 75^a, relay 55^a and conductor 73^a to condenser 57^a. Due to the charge on the condenser, the relay is energized, drawing up its armatures 63^a and 68^a, whereby it closes a circuit for itself through conductors 78^a and 72^a, magnet 60^a, conductor 61^a, contacts 63^a and 62^a to conductor 77^a and ground. From the sleeve contact 65 of the jack, the preliminary impulse circuit goes out on the other side of the line through conductors 7^a and 74^a to contact 69^a and armature 68^a where the line wires are short circuited. From this point the circuit continues to contact 67^a, conductor 70^a, relay 71^a, stepping mag-

net 60^a, and conductor 61^a to ground. The two branches of the circuit traversing the stepping magnet in parallel, it is energized so that the disks in all the substations except that calling are moved one step along the dash line path of Fig. 24, whereby the contacts 167' and 168' will remain open until closed by one of the pins 52', the pin N' being on the non-talking side of the disk. In the calling station, however, the one-step movement of the disk catches the pin N' on the talking side of the disk, which was moved from the Fig. 28 position, so that said pin retains the contacts 167' and 168' closed.

Having ascertained the desired station, the operator inserts her calling plug P' in the proper jack, producing a preliminary impulse which moves all the disks in the called line one step, as before described, in connection with the calling line, thus precluding the possibility of closing contacts 167' and 168' except by means of a pin 52', and she then dials until the disk D' of the desired substation has moved far enough to close contacts 167' and 168' by means of pin 52'. The ringing key 169 is then thrown, closing the ringing circuit which, in the called substation is from line 7^a, conductor 75^a, bell 180^a, condenser 123^a, closed contacts 168' and 167' and back to line 18^a.

The speaking circuit in the substation is from conductors 7^a and 75^a, the primary winding p of the inductance coil, conductor 12^a, contacts 11^a and 10^a, transmitter 9^a and contacts 168' and 167' back to the line 18^a. Variations in this circuit due to transmitter action induce, in well known manner a current through the secondary windings of the coil, condenser 123^a, transmitter 9^a, contacts 10^a and 129, and receiver R^a back to the winding.

When the conversation is completed and the calling and called parties both hang up their receivers, the projections 51' are retracted as indicated by dotted lines in Fig. 27, and as the operator steps the disks to zero, the pin N' in the calling substation rides against the outside or talking side of the disk until it enters the slow 49'. The remaining movement of the disks to the zero position brings the groove 48' opposite the pin N', with the projection 51' in position to push out the pin the next time the receiver is removed from the hook. In the called substation the zeroizing of the disk brings the groove 48' opposite the pin, as shown by the light dash lines in Fig. 24. In all the other substations, also, the disks move from their preliminarily, once-stepped position to the zero position, the pins following the path of Fig. 29.

Should, however, either or both parties to the call fail to hang up, zeroizing of the disk brings the pin N' to a position behind

the projection 51', the pin resting on top of the arm 51, whose surface is flush with the lower surface of the disk D'. In this position, shown at the right hand side of Fig. 28, the substation cannot call the exchange, because the pin is prevented from being pushed through the groove to the talking side. And even if the receiver should be hung up after the disk is zeroized so that the pin rests behind the projection, the substation will still be unable to call the exchange. However the central operator can call the thus locked out substation by dialing until a pin 52', is brought to the position where it closes contacts 167' and 168', and when the conversation is completed and the receiver hung up, normal conditions will be restored.

What is claimed is:—

20 1. In a selective system of party line telephony, the combination with a central station, a plurality of sub-stations electrically connected therewith, and selecting means at the central station of a circuit controlling device at each sub-station, a telephone at each sub-station, a switch for each telephone controlled by a member of the telephone, means at each sub-station under the sole mechanical control of a member of the telephone switch and cooperable mechanically with the circuit controlling device to place the sub-station in a talking circuit with the exchange station and means whereby the talking circuit may be made effective at the exchange station.

35 2. In a selective system of party line telephony, the combination with an exchange station and a plurality of substations connected electrically, of a selecting device at the exchange station, a source of energy at the exchange station, a circuit controlling device at the substation, a transmitter, a receiver, and a receiver hook at the substation, means under the sole mechanical control of the receiver hook and cooperable mechanically with the circuit controlling device to place the substation in a talking circuit with the exchange station and means whereby the talking circuit may be made effective at the exchange station.

50 3. In a selective system of party line telephony, the combination with an exchange station and a plurality of substations connected electrically, of a selecting device at the exchange station, a source of energy at the exchange station, a circuit controlling device at the substation, a transmitter, a receiver, and a receiver hook at the substation, means under the sole mechanical control of the receiver hook and cooperable mechanically with the circuit controlling device to place the substation in a talking circuit with the exchange station, and a selected substation and means whereby the talking

circuit may be made effective at the exchange station.

4. In a selective system of party line telephony the combination with an exchange station and a plurality of substations connected electrically, of a selecting device at the exchange station, a circuit controlling device at the substation, a source of energy at the exchange station, a transmitter, a receiver, and a receiver hook at the substation, means under the sole mechanical control of the receiver hook for signalling the exchange station and cooperable mechanically with the circuit controlling device to place the substation in talking circuit with the exchange station and means whereby the talking circuit may be made effective at the exchange station.

5. In a selective system of party line telephony the combination with an exchange station and a plurality of substations connected electrically, of a selecting device at the exchange station, a source of energy at the exchange station, a circuit controlling device at the substation, a transmitter, a receiver, and a receiver hook at the substation, means under the sole mechanical control of the receiver hook for signalling the exchange station and cooperable mechanically with the circuit controlling device to place the substation in talking circuit with the exchange station and a selected substation and means whereby the talking circuit may be made effective at the exchange station.

6. In a selective system of party line telephony the combination with an exchange station and a plurality of substations connected electrically, of a selecting device at the exchange station, two sources of electrical energy and of different characteristics at the exchange station, a circuit controlling device at the exchange station, a receiver, a receiver hook and a call-up alarm at the substation, means controlled by the circuit controlling device for closing the call-up alarm through the operation of the selecting device, means under the sole mechanical control of the receiver hook and cooperating mechanically with the circuit controlling device to place the substation in talking circuit with the exchange station and for cutting out the call-up alarm and means whereby the talking circuit may be made effective at the exchange station.

7. In a selective system of party line telephony the combination with an exchange station and a number of electrically connected substations, of a selecting device and at least one source of energy at the exchange station, means at the exchange station for sending out selecting impulses in parallel on both sides of the line connecting the exchange and substations, a connection be-

tween one side of the line and the ground at each substation, a stepping magnet at each substation, a circuit for said magnet connected to be traversed by the impulse sent out on the one side of the line, a relay in the circuit connection between one side of the line and the ground and adapted, on actuation, to connect the other side of the line with the magnet circuit, whereby said circuit is traversed by both impulses in parallel, a circuit controlling disk to be stepped by the magnet, a receiver and a receiver hook at the substation, talking contacts cooperating with the disk, and means controlled by the position of the receiver hook to cooperate with the disk so as to close the talking contacts in the calling substation.

8. In a selective system of party line te-
lephony the combination with an exchange
station and a plurality of substations con-
nected electrically, of a selecting device at
the exchange station, a source of energy at
the exchange station, a receiver, and a re-
ceiver hook at the substation, a circuit con-
trolling device at the substation, and includ-
ing a step by step mechanism having a disc
with a plural diameter periphery, forming

two guideways in communication with each other, a switch for controlling the communi-
cating point therebetween and means under
the control of the receiver hook for moving
said switch into and out of closing position.

9. In a selective system of party line te-
lephony the combination with an exchange 35
station and a plurality of substations con-
nected electrically, of a selecting device at
the exchange station, a source of energy at
the exchange station, a receiver, and a re-
ceiver hook at the substation, a circuit con-
trolling device at the substation, and includ-
ing a step by step mechanism having a disc
with a plural diameter periphery, forming
two guideways in communication with each
other, a switch for controlling the communi-
cating point therebetween, means under
the control of the receiver hook for moving
said switch into and out of closing position. 40

45 In testimony whereof I have affixed my
signature.

ELIZABETH FULLER HASTINGS,
Executrix of the Estate of Ruben Christopher Miller Hastings, Deceased.
